UNITED STATES PATENT OFFICE.

EDWIN B. MAGILL, OF LA CROSSE, WISCONSIN.

HAT-STAND.

SPECIFICATION forming part of Letters Patent No. 623,727, dated April 25, 1899.

Application filed May 9, 1898. Serial No. 680,111. (No model.)

To all whom it may concern:

Be it known that I, EDWIN B. MAGILL, a citizen of the United States, and a resident of La Crosse, in the county of La Crosse and State of Wisconsin, have invented an Improved Hat-Stand, of which the following is a specification.

This invention relates to hat-stands, and relates particularly to hat-stands designed and adapted for display purposes.

Among the objects of my invention is to provide a hat-stand adapted to engage the hat inside and to support it in any desired position and which admits of the hat being thoroughly examined without handling it.

In the preferable form thereof now known to me a hat-stand embodying my invention comprises a rod, arms, an end of each of which is pivoted to said rod, a spring or springs for maintaining said arms normally extended, means connecting said arms to cause simultaneous movement thereof, a lever pivoted between its ends to said rod, and a link connecting one end of said lever with an arm between the pivoted and free ends of the latter.

The invention also consists of the various other features, combinations of features, and details of construction hereinafter described and claimed.

In the accompanying drawings a hat-stand of my invention is fully illustrated.

Figure 1 is a side view of a hat-stand embodying my invention, showing the supporting-arms in their normal extended position in full lines and showing a hat supported on said stand in dotted lines. Fig. 2 is a top plan view of my improved hat-stand. Fig. 3 is an enlarged side view of the supporting-arms and adjunctive parts, said arms being in extended position and one thereof being shown in section; and Figs. 4, 5, and 6 are enlarged details.

Referring now to the drawings, A designates arms the corresponding ends of all of which are pivoted to a head A', formed on or rigidly secured to the upper end of a rod A². The outer or free ends of the arms A are designed to bear directly against the sides of the hat and are preferably outwardly curved or bent to form rings, thus insuring against the formation of exposed sharp points, which

would be liable to catch in said hat. Preferably, also, the portions of said arms which come into contact with the hat are provided with a covering a, of rubber or the like, which will materially increase the frictional engagement between said arms and the sides of the hat.

To provide for moving the arms A pivotally to cause the outer or free ends thereof to approach each other, so that they may be inserted into a hat, means are provided as follows: Pivoted to the arms A, between the pivoted and free ends of the latter, are links a', the opposite ends of all of which are connected to a sleeve A³, which is longitudinally movable on the rod A². It is thus obvious that pivotal movement of one of said arms will impart a corresponding movement to all of the others. Pivoted between its ends to the rod A², below the ring or sleeve A³, is a lever A⁴, one end of which is connected by a link a² with one of the arms A between the pivoted and free ends of the latter. The end of the lever A⁴ opposite to that to which the link a² is attached is downwardly bent or deflected, so that both said downwardly-bent portion of said lever A⁴ and the rod A² may be conveniently grasped with one hand, thus affording a purchase for operating said lever. Inserted between the head A' and the sleeve A³ and about the rod A² as a guide is a coiled spring A⁵. Said spring A⁵ is normally longer than the maximum distance between said head A' and said sleeve A³, and will thus operate to maintain said sleeve normally depressed and, through the links a', the arms A normally extended. The lever A⁴ is preferably so located that it will form a stop to limit the movement of the sleeve A³ under the influence of the spring A⁵, and thus operate to determine the normal extended position of the arms A.

The standard of my improved stand may obviously be formed by an extension of the rod A², the end of which is secured to any desired base or support and which may be either straight or bent to form a bracket. Preferably, however, the rod A² is made relatively short and is fitted to the tubular end a³ of a separate rod A⁶, the opposite end of which is secured in a suitable support. Provision is thus made for conveniently turning a hat-supported upon the arms A so that it may be

viewed on all sides. A further advantage of this construction is that a removable frame or holder, consisting of the rod A^2 , the arms A , and adjunctive parts, is provided by means of which a hat may be picked up for examination and inspection without handling the same directly, thus insuring against soiling or disarrangement.

In the construction shown the supported 10 end of the standard A^6 , which forms a bracket, is square, as shown at a^4 , and is fitted to a square socket a^5 , formed in a plate A^7 , adapted to be secured to a wall or other support, the relation being such that said bracket will 15 project from said wall or support at a desired angle.

I claim—

1. In a hat-stand the combination of a rod, arms, an end of each of which is pivoted to 20 said rod, a spring or springs for maintaining said arms normally extended, means connecting said arms to cause simultaneous movement thereof, a lever pivoted between its ends to said rod and a link connecting one end of 25 the lever with an arm between the free and pivoted ends of the latter, substantially as described.

2. In a hat-stand the combination of a rod, arms pivoted at one end to said rod, a sleeve 30 longitudinally movable on the rod, links con-

nected at one end to the sleeve and at their other ends to the arms at points between their pivoted and free ends, a spring normally maintaining the sleeve distant from said arms and the arms extended, a lever pivoted between its ends to said rod and a link connecting one end of the lever to an arm between the pivoted and free ends of the latter, substantially as described. 35

3. In a hat-stand, the combination of a rod, 40 arms pivoted thereto, a spring or springs applied to said arms and adapted to maintain the same normally extended, a sleeve longitudinally movable on said rod, links which connect said sleeve with said pivoted arms at 45 points a distance from their points of pivotal attachment to said rod, a lever pivoted to said rod in position to arrest the movement of said sleeve and the outward pivotal movement of the pivoted arms under the influence of the 50 spring or springs applied thereto, and a link which connects said lever to an arm, substantially as described.

In testimony that I claim the foregoing as my invention I have hereunto set my hand 55 this 4th day of May, 1898.

EDWIN B. MAGILL.
